FIG-3-

UNITED STATES PATENT OFFICE.

GEORGE WASHINGTON BELL, OF ST. JOSEPH, MISSOURI.

TRUSS.

SPECIFICATION forming part of Letters Patent No. 425,159, dated April 8, 1890.

Application filed July 31, 1889. Serial No. 319,273. (No model.)

To all whom it may concern:

Be it known that I, GEORGE WASHINGTON BELL, a citizen of the United States, residing at St. Joseph, in the county of Buchanan and State of Missouri, have invented a new and useful Truss, of which the following is a specification.

This invention has relation to trusses; and among the main objects in view are to provide a truss adapted to be adjusted to different-sized persons and to conform to different portions of the anatomy and varying characters of hernias, and which will give ease and comfort to the wearer.

With these general objects in view the invention consists in certain novel features of construction hereinafter specified, and particularly pointed out in the claims.

Referring to the drawings, Figure 1 is a perspective of a truss constructed in accordance with my invention. Fig. 2 is a transverse section of one of the rear pads; Fig. 3, a similar view of one of the front pads; Fig. 4, a detail, in rear elevation, of one of the front pads and illustrating its adjustable connection with the truss-braces. Fig. 5 is a detail of a modification hereinafter described. Fig. 6 is a detail perspective of the swivel.

Like numerals of reference indicate like parts in all the figures of the drawings.

1 represents the usual opposite side-spring body-bands which embrace the sides of the wearer, and 2 represents opposite back pads, which consist of an inner core 3, of leather, and 35 an outer facing 4, of chamois, the edges of which are secured at the rear side by a metal securing-plate 5, screwed thereto and into the core. At the opposite ends of the plate are provided studs 6, and upon the same is mounted a semi-elliptic flat spring 7, the ends of which are slotted, as at 8, to receive the studs and to permit of the yielding movement of the spring. A clip 9 embraces the spring and also receives the rear portion of one of the body-bands 1, said flat springs and body-bands being maintained in an adjusted position by means of a set-screw 10, inserted through a clip. A pad thus constructed is mounted upon each of the body-bands 1.

50 11 represents an intermediate rear metal adjusting-strap, and the same is provided with a series of perforations 12 near each end,

through which is passed a screw 13 into the pads. By moving the strap so that the screws will take into a different opening said strap 55 may be adjusted so as to bring the pads and side springs nearer together or farther apart. Any unnecessary projecting portions of the adjusting-strap may be removed, if desired.

14 represents a cylindrical ratchet-faced 60 stud, the shank 15 of which is riveted at 16 to one of the front ends of the body-bands 1. A stud thus constructed is mounted upon each of the body-bands.

17 represents a swivel or socket mounted 65 upon the stud and provided at one side with a lug 18, on which is mounted a spring-ratchet tooth 19, operating through an opening 20 in the swivel upon the face of the stud. A set-screw 21 is inserted through the swivel and 70 terminated within an annular recess 22, formed in the end of the stud, whereby a separation of the stud and swivel is prevented. The swivel is also provided with a perforated ear 25 at its outer end, upon which is swiveled 75 by means of a screw 26 an arm 27, carrying the front pads 28.

The pads 28 consist of a core 29, of wood or other material, having an upper annular recess 30, in which is mounted a convoluted 80 wire spring 31, the outer terminal being connected with the core by having its end inserted therein, as at 32, and the inner terminal connected with the inner end of a plate 33, as at 34, said plate being mounted in a 85 radial recess 35, formed in the core, and having its outer end provided with a screw 36, the head of which loosely engages a slotted plate 37, screwed by screws 38 to the rear face of the pad and serving to secure the inner 90 edges of the chamois or other covering 39 to the core. An annular opening 40 is formed in the rear face of the core of the pad, and in the same is mounted a convolute spring 41, which is retained within its seat by means of 95 the rear slotted plate, which is provided with a central opening smaller than the spring and for the passage therethrough of a stud 41*, projecting from a sleeve 42, mounted on the swiveled pad-carrying arm, upon which it is 100 adjustable in all directions by means of a set-screw 45.

46 represents a front strap, preferably made of elastic, and provided with opposite eyes 47,

one of which engages one of the screws which connects the swiveled arm to the swivel and the other one of which removably connects with the opposite screw that connects the opposite swiveled arms and swivel, said screws having their heads provided with annular grooves 48 for this purpose. By this construction it is apparent that the entire truss is light and easy to the wearer, may be adjusted to fit broad and narrow backs, and that the pads are universally and easily adjustable, and may be brought to a proper position and are held yieldingly therein. It will also be apparent that by a manipulation of the screw at the rear of the front pads the plate that supports the springs therein may be raised or lowered at its front end, thus making the pads convex, flat, or concave.

Referring to Fig. 5, which is a modification of one of the front pads, the same consists of omitting the rear securing-plate applied to the core in the former construction and in the provision of a pair of straps intersecting each other at the center of the rear face of the core, each strap terminating in a slot for the reception of tapes. The means for adjusting the springs of the core are the same as before described. The pad thus constructed is designed for use with an ordinary bandage where it is unnecessary to employ the entire truss. The metal straps from the back of the core preferably have their extremities slightly bent away from the core, and, being formed of spring metal, serve as an additional spring to the pad.

It is obvious that the truss can be used as a double or single truss. As illustrated it is a double truss; but by taking out the set-screws in the spring-back that is attached to the back pad and using a half-web belt on opposite sides of the body it becomes a single truss.

The back pad can be mounted on a spring-band so it will lay on any part of the back or hips, according to the requirement, as a back pad is apt to injure the spine. The end of the spring-band to which the front pad is attached is so constructed that any one wearing it can regulate the pressure by loosening the ring-screw that fits in the slot at the end of the socket of the pad without removing the truss from the body. Then, pressing on the pad, the small spring-ratchet catches in the small notches on the socket as it turns, and by tightening the ring-screw it holds it solid.

The front pad can be used either as a convex or concave pad by using the ring-screw attached on back of pad attached to lever, which either draws in or lets out the wire spring.

Among the many advantages that I claim are: It can be used either as a double or single truss. Any one can regulate the pressure without removing the truss from the body.

The back pad can be mounted on the spring-band so it will lie on any part of the hip or back, and still the truss will have the same power to retain the hernia.

The front can be used either as convex or concave by tightening or loosening the ring-screw on back of pad attached to lever. The wire spring on front pad is perfectly easy and cool to the body. The front pad can be used either on the spring-band or can be used on a web-belt.

Having thus described my invention, what I claim is—

1. The combination, with one of the body-bands, of a pad the rear face of which is provided with opposite screws, a slotted spring-plate mounted on the screws, and a clip provided with a set-screw mounted on the band and embracing the side spring, substantially as specified.

2. In a truss, a pad consisting of an internal core having a recess, a coiled spring mounted in the recess, a covering mounted over the spring and core, and means for adjusting the spring to a convex, plane, or concave form, substantially as specified.

3. A pad for a truss, consisting of an inner core having an annular recess and a radial recess, in combination with a convoluted spring mounted therein, having one end secured to the core, a radial plate mounted in the radial recess and having its inner end secured to the inner end of a spring, and a set-screw passing through the back of the core for adjusting the plate, substantially as specified.

4. In a pad for a truss, the combination, with an inner core the face of which is annularly recessed and provided with a radial recess, of a convoluted spring secured to the annular recess, an adjusting-plate mounted in the radial recess and secured to the spring, an adjusting-screw passing through the rear of the core and secured to the outer end of the plate, and a spring-plate secured to the rear face of a core and taking under the head of the adjusting-screw, substantially as specified.

5. The combination, in a truss, with a supporting-arm, a sleeve having a set-screw adjustably mounted on the arm, and a stud extending from the sleeve, of a pad the core of which is provided with the annular recess upon its rear face, a convolute spring mounted in the recess and encircling the stud, and an annular plate encircling the stud, substantially as specified.

In testimony that I claim the foregoing as my own I have hereto affixed my signature in presence of two witnesses.

GEORGE WASHINGTON BELL.
